ARTHUR J. HALL, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROL SYSTEM FOR ELECTRIC MOTORS.

1,143,955.

Specification of Letters Patent. Patented June 22, 1915.

Application filed August 2, 1913. Serial No. 782,554.

To all whom it may concern:

Be it known that I, ARTHUR J. HALL, a subject of the King of Great Britain, and a resident of Wilkinsburg, in the county of 5 Allegheny and State of Pennsylvania, have invented a new and useful Improvement in Control Systems for Electric Motors, of which the following is a specification.

My invention relates to systems of control 10 for electric motors, and it has special reference to overload trip devices that are employed in control systems for railway and vehicle motors.

One object of my invention is to provide 15 a device of the above indicated character which shall be simple in construction, positive and reliable in operation, and adapted to effect the interruption of the main motor circuits under conditions of abnormal over- 20 load.

Another object of my invention is to provide 25 an overload trip device having particular adaptation for use in railway control systems of the multiple unit type, which shall embody auxiliary switch members connected in the energizing circuits of the line switches and positively held in engagement, but which may be released to open the energizing circuits under abnormal conditions.

30 Another object of my invention is to provide a remotely controlled reset device associated with the above mentioned auxiliary switch members and having its energizing coil circuit normally open, but adapted to be 35 closed under said predetermined abnormal conditions.

Another object of my invention is to provide 40 means whereby the reset device is prevented from being energized except when the line switches are open.

Heretofore, it has been customary to interlock the line switch energizing circuits with switch members carried by an overload electro-magnetic trip, in which case, the electrical connections of the interlock switches 45 were not uniformly good and were affected by the current traversing the motor circuits. Furthermore, the energization of the reset coils could be effected at any time, which 50 often resulted in damaged coils by reason of their being subjected to current for long periods.

According to my invention I overcome these difficulties and provide an overload

tripping device having auxiliary contacts 55 that are positively maintained in engagement under a definite pressure, irrespective of the motor current, and I also provide means for limiting the duration of the energization of the reset coil. 60

The single figure of the accompanying drawing is a diagrammatic view of a portion of the connections of an automatic multiple unit control system embodying my invention. 65

A complete diagram of connections and apparatus is not considered essential and, consequently, only a sufficient portion of the system is illustrated to enable a clear understanding of my present invention. 70

Referring to the drawing, the system shown comprises a supply circuit 1, a plurality of motors having armatures A¹ and A² and field magnet windings F¹ and F², a plurality of line switches LS¹ and LS², motor circuit switches M¹, M², G and JR, a transition switch J, a plurality of resistors R¹, R², R³, RR¹, RR², RR³ adapted to be connected in the motor circuits in both series and parallel operation, a plurality of switches 75 adapted to short-circuit said resistors, a switch marked "Limit switch" having its energizing coil in series circuit with one of said motors and adapted to be actuated in accordance with the current traversing the motor circuit, a hand operated switching device marked "Master controller" comprising a rotatable drum 3, and a set of stationary contact fingers 4 that are adapted to engage the drum along the position-indicating 80 lines a, b, c, and d for controlling the connections of the auxiliary energizing circuits, a resistor marked "Control resistor" connected between the supply circuit 1 and the ground G and provided with intermediate 85 taps for the purpose of delivering a reduced voltage to the auxiliary control conductors, and an electro-responsive device marked "Overload trip" for interrupting the energizing circuits of the line switches LS¹ and 90 LS² under abnormal current conditions. 95

All of the electrically operated switches LS¹, LS², M¹, M², R¹ to RR³, inclusive, G, J and JR are adapted to occupy open and closed positions, hereinafter termed "switch-in" and "switch-out" positions, and all of said switches are provided with auxiliary interlock switches through which the auxiliary 100 105

control circuits are interlocked, although, for simplicity and clearness, only a portion of the interlock switches are shown.

The "overload trip" comprises a movable member 6 that is provided with a plurality of movable switch members 7 and 8 which are respectively adapted to coöperate with sets of stationary contact terminals 9 and are resiliently supported by springs 10. Associated with the movable member 6 is an electro-magnet marked "Reset" that comprises a movable core 11, a stationary core 12 and an energizing coil 13. A spring 14 is disposed within a recess 15 in the stationary core 12 and normally acts against the movable core 11 and tends to effect the separation of the switch members 7 and 8 from their coöperating contact terminals 9. A movable member 16 is associated with a movable core 17 that is adapted to coöperate with a stationary core 18, said cores being magnetized in accordance with the current traversing the motor circuit through the agency of a coil 19 in circuit therewith. Under normal conditions, the movable member 16 is held in engagement with the end of the movable member 6 by means of a spring 20 which is interposed between the member 16 and a stationary frame or bracket 21. A movable auxiliary switch member 22 is resiliently supported upon a stem 23 forming a part of the movable member 16 and is adapted to coöperate with a pair of stationary contact terminals 24 under abnormal current conditions to complete a circuit through coil 13. Normally, the switch member 22 is disengaged from its coöperating terminals so that the energizing circuit of the "reset" device is open.

Assuming the connection to be as shown, the operation of the system is as follows:—A switch termed "control switch" is first closed to the left, after which the "master controller" is moved into position *a*, thereby completing a circuit from the supply circuit 1 through said "control switch," upper conducting portions 3^a of the "master controller," and "controller resistor" to ground G. From the "control resistor" a circuit is completed including conductor 30, the lower conducting portions 3^b of the "master controller," conductor 31, coöperating switch members 7 and 9 associated with the "reset" device and energizing coil of switch LS¹ marked "LS¹-coil" to ground G. The "LS¹-coil" is, of course, directly associated with the LS¹ switch but is shown as separated therefrom in the diagram for purpose of clearness and simplification thereof. The switch LS¹ is, therefore, closed. Immediately subsequent to this operation, a circuit is completed from conductor 31 including interlock switch M²—out, energizing coil of switch JR, interlocking switch J—out and interlock switch LS¹—in to the "control re-

sistor." The switch JR is, therefore, closed. At the same time, a circuit is completed from the "control resistor" through interlock switch LS¹—in and energizing coil of switch M¹ to ground. The closure of the switch M¹ is, therefore, effected concurrently with the closure of the switch JR. Having accomplished the closure of these switches, a main motor circuit is completed from the supply circuit 1 through switch 33, conductor 34, energizing coil 19 of the "overload trip" and thence to ground G through the following devices,—switch LS¹, resistor R, switch M¹, armature A¹, field magnet winding F¹, resistors R¹, R², R³, switch JR, resistors RR¹, RR², RR³, armature A², field magnet winding F², and "limit coil" of the "limit switch." Energy is thus supplied to the two series connected driving motors through all of the resistors and the said motors are, therefore, started into operation at slow speed.

In order to increase the speed of operation, the "master controller" is moved to its second notch marked "*b*" thereby completing an energizing circuit from the "master controller" through the "limit switch," provided, of course, that the motor current is not sufficiently great to cause said switch to disengage its contact members, and thence through interlock switch LS²—out, coöperating switch members 8 and 9 associated with the "reset" device, and the energizing coil marked "LS²-coil" of the switch LS² to ground. Upon the completion of this circuit, switch LS² is closed if normal circuit conditions obtain, the operation being governed by the action of the "limit switch" in accordance with the usual practice. The closure of switch LS² short circuits resistor R and allows the motors to increase in speed. Resistors R¹ to RR³ are then short-circuited in accordance with the action of the "limit switch," although no description thereof will be given.

By moving the "master controller" consecutively to positions *c* and *d*, the motor connections are changed over to parallel arrangement with all the resistors R¹ to RR³ in circuit, after which the resistors are again automatically short circuited until the motors are operated in parallel directly across the line.

It will be noted that the line switches LS¹ and LS² constitute the circuit interrupters of the system, and their energizing coils are interlocked with switches 7 and 8 of the "reset" device and are, therefore, dependent upon the operation of the "overload trip".

If it be assumed that an abnormal current traverses the motor circuits, including the energizing coil 19 of the "overload trip", the movable core 17, its associated member 16 and switch member 22 are raised, thereby releasing the movable member 6 and asso-

ciated contact members 7 and 8, and also causing the switch member 22 to engage its contact terminals 24. As soon as the member 16 is disengaged from the end of member 6, the spring 14 forces the switch members 7 and 8 to disengage their contact terminals 9 and thus interrupt the energizing circuits of the switches LS¹ and LS². Thus, switches LS¹ and LS² are caused to open the main motor circuit. Inasmuch as the member 16 has been raised to its upper position, the member 6 prevents it from again dropping and thus maintains the switch members 22 and 24 in engagement, making it possible to energize the "reset" coil 13 by moving the "control switch" to its right position. In this event, energy is supplied to the "reset" coil through the "control switch", resistor 35, coil 13 and switch members 22 and 24 to ground G. Upon the energization of the "reset" coil 13, its movable core 11 and member 6, together with the switch members 7 and 8, are moved to the left, thereby permitting members 16, 17 and their associated switch member 22 to drop to their normal positions. At the same time, the switch members 7 and 8 again cooperatively engage their contact terminals 9, thereby permitting the normal operation of the control system in the manner hereinbefore set forth.

Attention is directed to the fact that the auxiliary switch members 7 and 8 are maintained in engagement with their contact terminals 9 under a definite and positive pressure which is unaffected by the current traversing the coil 19 of the "overload trip", and, as long as the energizing circuits of the line switches LS¹ and LS² are completed, it is impossible to energize the "reset" coil by reason of the interruption of its circuit at the switch members 22 and 24. The "reset" coil, therefore, may be energized only after the "overload trip" has operated and then, only for the short interval of time that is required for the actuation of the movable parts of the "reset" device.

I have shown and described my invention in connection with an automatic multiple unit control system merely for illustrative purposes and not with the intention of being restricted to such a type of system.

Various modifications in the arrangement of apparatus and circuit connections may be effected without departing from the spirit and scope of my invention.

I claim as my invention:

1. A switching device comprising stationary and movable magnetizable cores, an energizing coil therefor, a switch member associated with said movable core, a latch adapted to mechanically restrain said core and switch member in their closed positions, an electro-responsive device for releasing said latch, and a switch member associated there-

with and included in a circuit to be governed, said electro-responsive device having its coil in circuit with said first switch member.

2. A switching device comprising co-operating relatively movable switch members, means normally tending to separate said members, an electromagnet for opposing said means, electro-responsive means normally adapted to retain said switch members in engagement and adapted to release them under predetermined conditions and an auxiliary switch member associated with said electro-responsive means for closing the circuit of said electromagnet under said conditions. 70

3. A switching device comprising relatively movable co-operating switch members included in a circuit to be controlled, means normally tending to disengage said members, and means for opposing said disengaging means, of means adapted to retain said switch members in engagement and dependent upon abnormal circuit conditions for permitting their separation, and means associated with said retaining means for effecting the operation of said opposing means. 75

4. A switching device comprising co-operating switch members included in a circuit to be controlled, resilient means for separating said switch members, a latch for preventing said separation under normal conditions, an electromagnet for governing the operation of said latch in response to current conditions of an electric circuit, switch members associated with said latch and normally disengaged, and a reset electromagnet in circuit with said last named switch members and adapted to be energized for effecting the engagement of the switch members in the circuit to be controlled. 90

5. The combination with an electric circuit and an electrically operated switching device included therein, of an auxiliary switching device included in the energizing circuit of said electrically operated device and normally restrained in its closed position, an electro-responsive device in said electric circuit for governing the operation of said auxiliary switching device in accordance with current conditions of said electric circuit, electro-magnetic means for closing said auxiliary switching device, and means for limiting the duration of energization of said electromagnetic means. 100

6. In a control system, the combination with an electric motor, a circuit interrupter in circuit therewith, an electromagnetic device dependent upon said motor current and having normally separated contact members, a latch for restraining said device in its closed position and co-operating switch members associated with said latch and governing the operation of said circuit interrupter, of an electromagnet for releasing said latch and having its energizing coil in circuit with 110

the switch members of said electro magnetic device.

7. The combination with an electro-magnetic overload device having normally separated auxiliary contact members, of means for latching said device in its closed position, an electro-magnet for releasing said latch having its energizing coil in circuit with said auxiliary contact members.

10 8. The combination with an electric circuit, and an electro-responsive switching device influenced by the current in said circuit and normally adapted to occupy its open position, of mechanical means for positively 15 latching said switching device in its closed position and a releasing electro-magnet associated with said mechanical latching means for withdrawing said means and having an energizing coil interlocked through said

switching device whereby said coil is energized only for a predetermined short interval of time.

9. The combination with coöperating switch members normally held out of engagement, and a latch for retaining said switch members in engagement when once effected, of electrical means for releasing said latch and having its energizing circuit interlocked with said switch members and completed only when the switch members are in coöperative engagement.

In testimony whereof, I have hereunto subscribed my name this 26th day of July, 1913.

ARTHUR J. HALL.
